UNITED STATES PATENT OFFICE.

JOHN H. STOELT, OF SEBEWAING, MICHIGAN.

LIFE-BOAT.

No. 904,372.

Specification of Letters Patent. Patented Nov. 17, 1908.

Application filed August 23, 1907. Serial No. 389,880.

To all whom it may concern:

Be it known that I, JOHN H. STOELT, a subject of the Emperor of Germany, residing at Sebewaing, in the county of Huron 5 and State of Michigan, have invented new and useful Improvements in Life-Boats, of which the following is a specification.

This invention relates to an improved life boat adapted to be carried by passenger and 10 other vessels for emergency use in the event of ship wreck; and the invention has for its object to provide a boat of this character which shall be simple in construction and efficient in operation; which may be readily 15 and safely launched; which shall be self righting; which, if it should be carried with a foundering vessel below the surface of the water, will speedily rise to the surface; which shall be covered over so that the oc- 20 cupants will be protected from the elements; which shall be provided with means for propulsion operable from the inside; and which shall possess superior advantages in point of simplicity, durability and general 25 efficiency.

With these and other ends in view which will readily appear as the nature of the invention is better understood, the same consists in the improved construction and novel 30 arrangement and combination of parts which will hereinafter be fully described and particularly pointed out in the claims.

In the accompanying drawing has been 35 illustrated a simple and preferred form of the invention, it being, however, understood that no limitation is necessarily made to the precise structural details therein exhibited but that changes, alterations and modifications within the scope of the claims may be 40 resorted to when desired.

In the drawings:—Figure 1 is a side elevation of a life boat constructed in accordance with the invention. Fig. 2 is a longitudinal vertical sectional view of the same. 45 Fig. 3 is a vertical transverse sectional view taken on the plane indicated by the line 3—3 in Fig. 2. Fig. 4 is a detail view of the spur wheel 7. Fig. 5 is a detail plan view.

Corresponding parts in the several figures 50 are denoted by like characters of reference.

The improved life boat in its preferred

form consists of an approximately cylindrical body A which is secured upon and suitably connected with an elongated keel member B preferably consisting of a metallic casting which is sufficiently heavy to cause the boat to be self righting; said keel member being formed with a downwardly extending longitudinal rib 1 which constitutes the keel, and with an elongated tubular passage 2 wherein the propulsion member is mounted, as will be presently fully described. The tubular passage 2 has been illustrated as being provided with a lining 3, which may be interiorly polished so as to present a smooth and non-obstructive anti-friction surface. The tubular passage is provided with cross-pieces 4 affording bearings for a shaft 5 carrying a plurality of propellers 6 and carrying also a spur wheel 7 which is connected by a train of gearing 8 with a shaft 9 supported for rotation inside of the body of the boat and having a hand wheel 10 whereby it may be operated for the purpose of transmitting motion to the propeller shaft. The tubular passage and the lining of the latter is provided with enlarged portions 11 adjacent to the cross bars 4 and to the gearing for the purpose of permitting water to pass freely through the said passage without being materially obstructed by said cross bars and gearing. The spur wheel 7, is moreover, of skeleton construction, being provided with spokes 12 which latter are preferably set 85 slantingly, as will be seen in Fig. 4 of the drawings, thus transforming the spur wheel into a propeller which will assist in the propulsion of the boat.

The body A of the boat may be constructed in any suitable and convenient manner of matched or lapped lumber, and the forward portion of the body is protected and reinforced by a sheathing 13 of sheet metal. The rib 1 constitutes the keel which projects 90 rearwardly of the body of the keel member B, as will be clearly seen in Figs. 1 and 2, and it affords a bearing for the lower extremity of the post 14 carrying the rudder 15 which latter is accommodated in the space 100 between the keel 1 and the stern post 16 through which the rudder post extends, said

rudder post being provided at its upper end with a cross bar or lever 17 to the ends of which the steering lines 18 are attached; said lines being guided through casing tubes 19 to a conveniently accessible point within the body of the boat.

The body of the boat is provided at intervals with transverse partitions 20 which not only serve to brace and reinforce the structure, but which also divide the body of the boat into a plurality of water tight compartments 21; the partitions 20 being provided with apertures 22 sufficiently large to permit passengers to pass therethrough, and provided with suitable closures 23. The compartments of the boat are accessible through hatch ways 24 in the deck or upper portion of the boat; said hatch ways being provided with tightly fitting hatches 25 which are preferably constructed in such a manner as to be perfectly water tight. The compartments of the boat are provided with seats 26 which are preferably arranged lengthwise, along the sides of the compartments, so as to enable the occupants to pass from one end of the boat to the other conveniently and without discommoding each other. At the stem and at the stern of the boat are formed air chambers 27, and air tanks 28 are suitably arranged lengthwise in some of the compartments for the purpose of assisting the boat in rising to the surface of the water in case it should become submerged. Suitably constructed water proof lockers 29 are also provided at various places for water and provisions. Dead-lights 30 are inserted at various places in the sides of the boat for the purpose of affording light to the occupants.

The operation and advantages of this invention will be readily understood from the foregoing description taken in connection with the drawings hereto annexed by those skilled in the art to which it appertains.

The improved life boat may be carried upon the deck of a vessel, or it may be slung from suitable davits, or it may be supported upon a suitably constructed slide which will enable it to be readily launched in case of emergency. It is intended that the boat shall be constantly supplied with water and provisions, and that the air chambers and tanks shall be kept tightly closed. In case of emergency, the passengers and crew may enter the compartments of the boat through the hatch ways of the latter, the crew being instructed by previous drills how to take their stations and how to manipulate the boat. If time permits the boat will be promptly launched, but if in the event of sudden disaster the boat should go down with the vessel, it is intended that it shall be secured in such a manner that it will be-

come detached by its own buoyancy, induced by the air tanks and compartments, so that it will readily rise to the surface. The boat may be readily steered, and propelled either in a forward or rearward direction by properly rotating the propelling shaft; the propulsion of the boat being effected without necessity of opening the hatches or exposing the occupants to the elements. The hatches, however, may be slightly raised, at intervals, for the purpose of supplying fresh air.

The improved life boat will be manageable and efficient under circumstances where boats propelled by oars and provided with sails will be useless and unserviceable. The construction is simple; it will be found thoroughly efficient for the purposes for which it is provided.

Having thus described the invention, what is claimed as new, is:—

1. In a life boat a cylindrical body, an elongated keel member having a longitudinal tubular passage provided at intervals with expanded portions, a propulsion member fitted in the passage and including a spur wheel arranged in one of the expanded portions of the passage, and cross bars constituting bearings for the propeller shaft disposed adjacent to the expanded portions. 85
2. In a life boat a cylindrical body, an elongated keel member having a longitudinal tubular passage, and a propulsion member fitted in said passage, said propulsion member including a propeller shaft and a spur wheel mounted upon said shaft having slantingly disposed spokes constituting propeller blades. 95
3. In a life boat a cylindrical body, a keel member having an elongated tubular passage and a rearwardly extended rib constituting a keel, a stern post connected with the cylindrical body, a rudder post extending through the stern post of the cylindrical body of the boat and stepped in the rearwardly extended keel, a rudder positioned between the stern post and the keel, and suitably guided steering lines connected with the rudder post. 105
4. In a life boat a cylindrical body having a plurality of transverse partitions provided with apertures and with closures for said apertures, seats arranged longitudinally in the compartments thus formed, air chambers at the front and rear ends of the boat, air tanks disposed longitudinally in the compartments of the latter, a keel member connected with the cylindrical body and having a longitudinal passage, a propulsion member supported for rotation in said passage, and means for operating said propulsion member including a train of gears arranged 115 within one of the compartments of the boat. 120
5. In a life boat a cylindrical body having a plurality of transverse partitions provided with apertures and with closures for said apertures, seats arranged longitudinally in the compartments thus formed, air chambers at the front and rear ends of the boat, air tanks disposed longitudinally in the compartments of the latter, a keel member connected with the cylindrical body and having a longitudinal passage, a propulsion member supported for rotation in said passage, and means for operating said propulsion member including a train of gears arranged 125 within one of the compartments of the boat.

5. In a life boat a cylindrical body having a plurality of compartments, a keel member of material of high specific gravity connected with the cylindrical body and having a longitudinal tubular passage, a propeller shaft supported for rotation in said passage, and means for operating said propeller shaft including a train of gears and a hand wheel

supported within one of the compartments of the boat.

In testimony whereof I affix my signature in presence of two witnesses.

JOHN H. STOELT.
